UNITED STATES PATENT OFFICE.

WILLIAM F. PAGEL, OF SYCAMORE, ILLINOIS.

PLUMBER'S BLOWTORCH.

Application filed August 4, 1923. Serial No. 655,625.

My invention relates to improvements in so-called plumber's blow or hand torches and has special reference to improvements in the construction of such torches with the object in view of reducing the transmission of heat from the burner to the reservoir, both for the purpose of eliminating difficulties in the fuel feed resulting from overheating the reservoir and for the purpose of making the torch more durable and more satisfactory in operation.

Specifically my invention relates to an improved manner of connecting the burner with the reservoir by which the connection of these two parts is greatly strengthened, whereby lateral strains or knocks on the burner cannot injure or loosen the connection and whereby the path that the heat must travel from the burner to the reservoir is so greatly lengthened that so little heat actually reaches the reservoir as to be practically negligible in operation.

My invention will be more readily understood by reference to the accompanying drawing forming part of this specification and in which the drawing represents a plumber's hand torch embodying my invention in one form.

In said drawing 1 represents the tank or reservoir of the torch and which is pressed out of sheet metal, the cylindrical wall 2 and top 3, being preferably formed of one piece without a seam and the bottom 4 made of another piece. The bottom is dished upwardly to strengthen it to withstand the internal pressure employed in operating the torch. One feature of my invention relates to the strengthening or stiffening of the flat top 3.

In the form shown I provide a hand pump 5 attached to the tank by rigid brackets or braces 6 and 7, through the lower one of which air enters the tank from the pump.

At the opposite side of the reservoir I insert a tubular member 8 which depends within the tank, preferably ending at about the middle of the height of the tank. The upper end of this tubular member is connected rigidly to the top wall 3 of the tank and is tightly sealed thereto. To form this connection I preferably reduce and externally thread the upper end 9 of the tube 8. I project the reduced end 9 up through an opening 10 in the top wall and I clamp the tube tightly to the top wall by a nut 11 screwed onto the reduced threaded end 10,

clamping the top wall between the nut 11 and the shoulder 12 formed by reducing the upper end. Finally all of the joints are thoroughly soldered, as shown at 9'. The lower end 13 of the tube 8 is internally threaded to receive the lower externally threaded end 14 of the burner feed tube 15 which leads from the lower end of the tube 8 to the superposed burner 16.

The feed tube is somewhat smaller in external diameter than the internal diameter of the tube 8, thus providing a free space 17 between the two which extends from the top of the tube 8 to the lower threaded end. 70 This space is sufficient to prevent the conduction of heat from the feed tube to the tank except by passing clear to the bottom of the tube 8. The lower end of the feed tube is tightly sealed in the tube 8 by soldering as indicated at 15' and as this joint is so far removed from the burner and is generally immersed in liquid, it cannot become so hot as to melt the solder, which is a source of frequent annoyance with the old type of torch in which the feed tube is soldered directly into the top wall of the tank. The annular insulation space 17 is small enough so that contact of the feed tube with the tube 8 prevents the feed tube being deflected beyond its elastic limit, and consequently immediately the pressure is removed, the feed tube returns to its central free position. The slight possible deflection of the feed tube is not sufficient to strain or break the soldered connection of the lower end of the feed tube.

In order that substantially all of the liquid fuel in the tank may be fed to the burner through the feed tube, I extend the feed tube to substantially the bottom of the tank. As shown in the drawings this is accomplished by an extension tube 18 which is rigidly screwed, at its upper end, into the lower end of the threaded lower portion 13 100 of the tube 8. The lower end 19 of the extension tube 18 is open.

For the purpose of strengthening the top wall 3 of the tank I deflect the lower portion 20 of the tube 18 outwardly into contact with the cylindrical wall of the tank near its lower end, as shown at 21, and I securely attach the tube to the wall of the tank preferably by means of solder, as shown at 22. Furthermore, I permanently seal the upper 110 end of the tube 18 in the lower end of the tube 8 by solder, as shown at 23. The ex-

tension tube 18 in conjunction with the tube 8 forms a tie between the top wall of the tank and the lower part thereof. In other words, I provide a tension member within 5 the tank to assist the thin top wall of the tank in resisting the internal pressure and I do this by means of the tube which serves the additional function of feeding the fuel from the tank to the burner. While the 0 means of feeding the fuel from the bottom of the tank to the burner is shown in the drawings as made up of the two tubes 18 and 15, the manner in which they are connected results practically in what may be 15 termed a unitary feed tube extending from the bottom of the tank to the burner. The tank is provided, as usual in this type of torch, with a filling opening 24 in its bottom adapted to be closed by a removable 20 screw plug 25, the dished bottom serving as a filling cup.

While I have described a specific embodiment of my invention, I do not thereby limit or confine my invention to the details of 25 such construction, the invention being broader in many aspects than the form shown and described.

I claim:

1. In a plumber's blow torch a sheet metal 30 reservoir, a burner arranged above the reservoir, a support tube having its upper end secured in the top wall of the reservoir and projecting down into the reservoir, a fuel feed tube having its lower end mounted in 35 the lower end of the support tube and the feed tube extending freely up through the support tube to the burner.

2. In a device of the kind described, a fuel 40 reservoir, a burner arranged above the reservoir, a fuel feed tube for the burner extending from the burner down through the top of the reservoir and ending within the reservoir, the opening in the top of the reservoir through which the feed tube passes 45 being slightly larger than the feed tube, and a support tube dependent within the reservoir its upper end mounted in the top wall of the reservoir, the lower ends of the two tubes connected and said tubes being 50 of such relative sizes that an air space is provided between them.

3. In a device of the kind described, a fuel 55 reservoir, a burner arranged above the reservoir, means for supporting the burner and conducting the fuel from the reservoir to the burner comprising a feed tube connected to the burner and projecting down through an opening in the top wall of the reservoir, the opening spaced from the side wall of the 60 reservoir, a support tube surrounding the feed tube sealed at its upper end to the top wall of the reservoir and connected at its

lower end to the feed tube between the top wall and the bottom of the reservoir and an extension feed tube extending from the lower 65 end of the support tube to the bottom of the reservoir, the lower end of the extension tube being connected rigidly to the body of the reservoir.

4. In a device of the kind described, a 70 liquid fuel reservoir, a burner arranged above the reservoir, means for feeding fuel from the bottom of the reservoir to the burner, comprising a tubular structure and composed of a feed tube connected to the 75 burner and extending within the reservoir, a support tube dependent within the reservoir the feed tube mounted in the lower end of the support tube and otherwise free of contact with the reservoir, and an extension 80 feed tube connected at its upper end to the lower end of the support tube and ending at its lower end adjacent to the bottom of the reservoir.

5. In a device of the kind described, a 85 fuel reservoir, a feed tube extending from the burner down through an opening in the top wall of the reservoir, a support tube within the reservoir surrounding the feed tube and free therefrom except at its lower 90 end where they are connected, the upper end of the support tube sealed to the top wall of the reservoir, and an extension feed tube extending down from the point of connection of the two tubes to a point adjacent to the connection of the bottom of the reservoir and the side wall and its lower end connected rigidly to the side wall of the reservoir as 95 by soldering.

6. In a device of the kind described, a 100 reservoir made of thin sheet metal, a burner above the reservoir, a tubular fuel feed member structure connected at its upper end to the burner and extending down through the top wall of the reservoir and connected thereto, the lower end of the structure metallically connected to the inner surface of the reservoir adjacent to the connection of the bottom and top whereby said structure 105 serves as a tension member to straighten 110 the top wall of the reservoir.

7. In a device of the kind described, a 115 pressure reservoir made of thin sheet metal and having a substantially flat top, a fuel feed tubular structure extending down through the tank and permanently connecting the top of the reservoir and the inner side of a wall of the reservoir adjacent to the bottom thereof, as and for the purpose specified.

In testimony whereof, I have hereunto set my hand, this 19th day of June, 1923.

WILLIAM F. PAGEL.
